PORTABLE GAS DISPENSER

Clement J. Olowinski, Erie, Pa.

Application February 25, 1949, Serial No. 78,423

8 Claims. (Cl. 128—203)

1

This invention relates to portable gas dispensers, and more particularly to a portable dispenser usable as an inhalator.

It is among the objects of the invention to provide a portable dispenser of a size and weight to be easily carried by the user and which will contain a supply of compressed gas, such as oxygen, so that the gas may be dispensed under manual control, as desired, by such persons as athletes, aviators and sportsmen to allay respiratory exertion, those persons suffering from asthma or other respiratory ailments, and those temporarily imbued with certain poisons, fumes, smoke or an excess of alcohol, which dispenser includes means for adding desired medicaments to the gas dispensed, can be easily recharged with compressed gas when the gas supply has been exhausted, and which is simple and durable in construction, economical to manufacture, of neat and attractive appearance, and extremely easy to use.

Other objects and advantages will become apparent from a consideration of the following description and the appended claims in conjunction with the accompanying drawings, wherein:

Figure 1 is a longitudinal side elevation of a portable gas dispenser illustrative of the invention;

Figure 2 is a longitudinal, medial cross-section of the dispenser illustrated in Figure 1;

Figure 3 is a longitudinal, medial cross-section similar to Figure 2, but taken in a plane substantially perpendicularly disposed to the section plane of Figure 2;

Figure 4 is a bottom plan view of the dispenser;

Figure 5 is a longitudinal cross-section on an enlarged scale of a flask-mounted, gas-control valve;

Figure 6 is a cross-section of the line 6—6 of Figure 2 showing a spring return for automatically closing the manually-operated valve of the dispenser;

Figure 7 is a cross-section of a fragmentary upper portion of the dispenser showing a baffle and medicament container mounted in operative position;

Figure 8 is a bottom plan view of the container and baffle illustrated in Figure 7;

Figure 9 is a bottom plan view of the manually-operable valve mechanism with the flask and flask-mounted valve detached therefrom.

With continued reference to the drawings, the improved dispenser comprises a cylindrical container or receptacle 10 of a size to render the gas dispenser easily portable while at the same time containing a reasonably large supply of

2

compressed gas. An internal bead 11 is formed in the container 10 at one end of the latter, and an end wall 12 is secured in the opposite end of the cylindrical container. This end wall has an annular flange 13 which fits closely into the container 10 at the end of the container opposite the internal bead 11 and is secured therein by cement or other suitable means. The container 10 may be formed of a rigid and durable substance, such as metal, while the end wall structure 12 is preferably formed of an easily moldable material, such as a suitable synthetic resin plastic.

As is clearly illustrated in Figures 2 and 3, the end wall 12 is made concave within the flange 13, and is provided at diametrically-opposite sides with rounded projections 14 and with curved marginal edges extending between such rounded extensions to constitute a mouthpiece for the convenient inhalation of the gas contained in the dispenser.

An elongated, generally cylindrical valve body 15 extends inwardly of the container 10 from the center of the mouthpiece end wall 12 and is provided with a centrally-disposed, longitudinally-extending bore 16 having respective, screw-threaded counterbores 17 and 18 in its opposite ends. The counterbore 17 opens to the interior of the mouthpiece end wall 12, and the counterbore 18 opens to the inner end of the valve body 15. The valve body 15 may have, at its opposite ends, annular enlargements or beads 19 and 20 to reinforce the walls of the respective counterbores 17 and 18.

Intermediate its length the valve body 15 is provided with a transverse, tapered aperture 21, and a rotatable valve plug 22 having a transverse passage 23 therethrough is rotatably mounted in the aperture 21. The smaller end of the valve plug 22 is provided with a screw-threaded well into which is threaded a headed screw 24, and a compression spring 25 interposed between the head of the screw 24 and a bearing washer 26 disposed against the outer surface of the valve body 15 surrounding the smaller end of the aperture 21, maintains the valve plug 22 firmly seated in the aperture 21 in gas-tight association with the valve body 15. The larger end of the valve plug 22 is provided with an outwardly-extending boss 27 having a screw-threaded well therein into which is threaded the reduced, externally screw-threaded end portion of a valve shaft 28 which extends from the larger end of the valve plug through an aperture 29 in the wall of the container 10, and a valve-turning knob 30 is secured on the outer end of shaft 28 at the outside of the container 10.

With this arrangement, the valve plug 22 may be rotated by the knob 30 to align the passage 23 in the valve plug with the adjacent ends of the bore 16 in the valve body 15, and thereby open this manually-controlled valve, when desired.

In order to prevent the waste of gas from the dispenser, the valve is closed by suitable spring means, such as that particularly illustrated in Figure 6.

The side of the valve body 15 in alignment with the large end of the transverse opening 21 is flattened at the inner end of the valve body, and a bracket 31 is secured to this flattened portion of the valve body 15 by suitable means, such as the screws 32. The bracket 31 is a flat, L-shaped body having an arm 33 which projects laterally outward from the valve body 15 and is provided with an aperture near its outer end. This bracket 31 also includes a portion 34 which extends inwardly of the valve body 15 to a location adjacent the boss 27 on the large end of the valve plug and is there provided with a terminal straight edge which is disposed substantially transversely of the valve body.

A lever 35 is provided, at one end, with an enlarged, apertured lug 36 which receives the non-circular boss 21, and the lever is also provided with an outwardly-projecting arm 37 provided with an aperture near its outer end. A tension spring 38 is connected at one end to the bracket arm 33 and at its opposite end to the lever arm 37 by having hooked end portions inserted through the respective apertures in the bracket arm and the lever arm, and resiliently turns the lever to a position in which the terminal straight edge of the portion 34 of the bracket is contacted by the adjacent straight edge of the lever arm. This provides a stop for the lever at which the valve plug is so positioned that its transverse passage is out of alignment with the adjacent portions of the bore 16 and the valve is closed. The valve is opened by rotating knob 30 in a direction to stretch the spring 38.

A hollow metal flask 40 is received in the cylindrical container 10 adjacent the inner end of the elongated valve body 15. This flask is formed of a strong, durable metal, such as alloy steel, and is of generally cylindrical shape with an outside diameter slightly less than the inside diameter of the container 10, so that the flask can be easily and conveniently positioned in the container. This flask has a substantially flat bottom wall 41 and a domed top wall 42 provided with a central, inwardly-directed boss 43 which is apertured and internally screw threaded.

A valve body, generally indicated at 44, has a central wrench-receiving portion 45 of hexagonal or other non-circular shape, and has at each side of said wrench-receiving portion respective externally screw-threaded bosses 46 and 47, the boss 47, in the arrangement illustrated, being threaded into the boss 43 of the flask. A central bore 48 extends longitudinally through the valve body 44 and through a cylindrical extension 49 which projects from the outer end of the boss 47, and this boss is reduced at the outer end of the cylindrical extension to provide an internal, annular shoulder 50. Valve mechanism such as is conventionally used in the tube valve stems of pneumatic tires is operatively disposed in the bore 48 of the valve body 44. As illustrated, this valve mechanism includes a cup-shaped spring abutment 51 bearing at its open end on the internal shoulder 50, a tubular valve seat 52 spaced from the abutment 51 and secured in the bore 75

by a hollow nut 53 which is threaded into the corresponding end of the bore 48 and surrounds a packing gland 54 which bears upon the adjacent end of the tubular valve seat 52, suitable packing 55 being interposed between the nut 53 and the packing gland 54. A slender valve stem 56 extends through the abutment 51, the tubular valve seat 52, the packing gland 54 and the nut 53, and a cylindrical valve head 57 is secured on this stem between the abutment 51 and the adjacent end of the valve seat 52. A compression spring 58 surrounds the stem between the abutment 51 and the valve head 57 and resiliently urges the valve head into sealing contact with the end of the valve seat, the valve head being provided with a suitable facing of resilient material, such as rubber, to seal the valve against the passage of gas therethrough from the interior of the flask 40. When the stem 56 is depressed, as illustrated in Figure 5, the valve head 57 is moved away from the valve seat 52 and the valve is opened.

In order to assemble the flask 40 with the container 10 and container end wall 12, the boss 46 of the valve body 44 is entered into the counterbore 18 in the inner end of the valve body 15, and the flask is then rotated to thread this boss 46 into the counterbore 18, a non-circular, wrench-receiving head or extension 59 being provided on the bottom wall of the flask to facilitate such rotation of the flask.

Before the boss 46 is entered into the counterbore 18, a valve-stem-depressing spider, generally indicated at 60, is inserted into the counterbore. This spider comprises an apertured disc 61 and a stem 62 which projects from the center of the disc and is directed toward the open end of the counterbore. As the boss 46 is threaded into the counterbore 18, the outer end of stem 61 contacts the adjacent end of valve stem 56, depressing the valve stem to move the valve head 57 away from the valve seat 52 against the force of spring 58 to thereby open the valve and connect the interior of the flask 40 with the bore 16 in the valve body 15, so that dispensing of the compressed gas from the flask 40 can be controlled entirely by manual movement of the rotatable valve plug 22 in the manner described above.

When the supply of gas in the flask 40 has been substantially exhausted, the flask can be removed from the container by threading the boss 46 out of the counterbore 18, whereupon the valve in the valve body 44 will close. The flask may then be recharged with gas under pressure, and the above-mentioned valve mechanism will retain the gas under pressure in the flask until the flask is again installed in the dispenser in the manner described above.

A threaded post 63 has, at one end, an externally, screw-threaded, slotted plug or spider 64 which is threaded into the counterbore 17 in the outer end of the valve body 15. A concavo-convex baffle, generally indicated at 65, has at the center of its concave side a hollow, internally screw-threaded boss 66 which is threaded onto the end of the stem 63 opposite the spider 64, so that the baffle is disposed in the bottom of the mouthpiece formation of the wall 12, and overlies the openings through the spider 64 to deflect gas issuing through the spider outwardly along the concave outer surface of the mouthpiece formation, the edges of the baffle being spaced from the concave outer surface of the mouthpiece formation to permit the free flow of gas between the baffle and the adjacent surface of

the mouthpiece formation. Diametrically-opposed fins 67 are provided on the convex side of the baffle to facilitate threading the baffle onto and off of the post 63.

A flat disc-shaped receptacle 68 is disposed between the baffle 65 and the spider 64, and is provided with a central aperture through which the post 63 extends. This disc-shaped receptacle is provided to contain a desired medicament to be added to the gas issuing into the mouthpiece formation of the device, and may be provided with porous walls to contain medicating material in crystal form or a wick saturated with such material in liquid form, or may have a honeycomb construction providing cells which are filled with a medicating material in plastic condition. This receptacle 68 may be removed and replaced, whenever desired, by threading the baffle off of the post 63.

A circular bottom end wall 70 closes the end of the cylindrical container 10 provided with the internal bead 11, and this wall is provided with a central opening 71 which receives the wrench-receiving extension 59 on the bottom of the flask 40. The disc-shaped bottom wall 70 is provided with a peripheral groove 72 which receives the bead 11, and, if the material of the cylindrical container has sufficient flexibility, and the groove 72 is made sufficiently shallow, the bottom wall may be snapped into and out of assembly with the container 10. Otherwise, the bead and the groove may be formed in spaced-apart, discontinuous sections, as indicated in Figure 4, so that the end wall can be set in place and then rotated through a predetermined angular interval to releasably lock it in operative assembly with the container.

A cup-shaped cover or lid 73 is provided to enclose the mouthpiece end wall 12 when the device is not in use. This cover has a flat end wall 74 and an annular, marginal flange 75 of a diameter to closely fit the outer surface of the flange 13 of the end wall, which flange projects beyond the adjacent end of the container 10, as is clearly illustrated in Figure 3, with the edge of the cap flange 75 at the open end of the cap bearing upon the end of the cylindrical wall of the container 10. This cap may be formed of metal, or other suitable material, such as synthetic resin plastic, and is preferably provided with suitable knurling 76 on its outer surface, so that it can be easily removed and replaced, when desired.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from

one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body.

2. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, said flask having an external, wrench-receiving formation on the end thereof opposite said boss.

3. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into

said boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, and a spring return connected to the rotatable valve plug in said first-mentioned valve body to resiliently return said valve plug to closed position after the same has been moved to open position by manual rotation of said valve-rotating knob.

4. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, and a deflector mounted in said counterbore at the mouthpiece end-wall end of said first-mentioned valve body and spaced from the adjacent surface of the mouthpiece formation in such end wall.

5. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said

boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, a deflector disposed in said mouthpiece end wall adjacent the outer surface of the mouthpiece formation in such wall and a medicament container disposed between said deflector and the adjacent surface of the mouthpiece formation in said end wall.

6. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said boss and having a bore extending longitudinally therethrough and an externally screw-threaded portion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, and a removable end wall in said one end of said container releasably secured in said container by said internal bead.

7. A portable gas dispenser comprising a cylindrical container having an internal bead at one end, an end wall secured in the opposite end of said cylindrical container and constituting a gas inhalator mouthpiece, an elongated valve body extending inwardly of said cylindrical container from the center of said end wall and having a longitudinally-extending bore therethrough provided in each end with a respective screw-threaded counterbore, a rotatable valve plug in said valve body intermediate the length of the latter, a valve-operating shaft extending from one end of said valve plug through the wall of said cylindrical container, a valve-rotating knob secured on said shaft outside said container, a hollow flask for gas under pressure received in said cylindrical container and having on one end wall an internally screw-threaded, apertured boss, a second elongated valve body threaded into said boss and having a bore extending longitudinally therethrough and an externally screw-threaded por-

tion threadable into the adjacent counterbore in said first-mentioned valve body, valve mechanism in the bore of said second valve body including a valve stem depressible to open said valve, and a stem-depressing spider secured in the counterbore of said first-mentioned valve body into which said second valve body is threaded to open the valve in said second valve body when said second valve body is threaded into said first-mentioned valve body and thereby connect the interior of said flask with the bore in said first-mentioned valve body, and a removable cap for said inhalator fitting over said mouthpiece end wall and bearing against the adjacent end of said cylindrical container.

8. A portable gas dispenser comprising an elongated, hollow container, an end wall secured in one end of said container, said end wall having

5 a marginal flange secured in said container and a concave mouthpiece formation within said flange, a hollow valve body extending inwardly of said container from the center of said end-wall mouthpiece formation, a valve in said valve body, manually-operated valve-actuating means extending from said valve to the exterior of said container, a gas-containing flask in said container, a second hollow valve body connecting 10 said flask to said first-mentioned valve body, and valve mechanism in said second valve body automatically opened when said second valve body is operatively connected to said first-mentioned valve body.
